GEORGE MATTHYSSEN, OF INGLEWOOD, AND CHARLES OHLSON, OF LOS ANGELES,
CALIFORNIA.

HEADLIGHT.

Application filed March 24, 1924. Serial No. 701,491.

To all whom it may concern:

Be it known that we, GEORGE MATTHYSSEN and CHARLES OHLSON, citizens of the United States, residing at Inglewood and Los Angeles, respectively, in the county of Los Angeles and State of California, have invented new and useful Improvements in Headlights, of which the following is a specification.

10 Our invention relates to headlights and consists of the novel features herein shown, described and claimed.

An object is to make a headlight having a reflector made in two pieces meeting on a horizontal diametrical plane, mount one piece of the reflector permanently, mount the other piece of the reflector for forward and backward adjustment, and mount a lamp socket for forward and backward adjustment so that by adjusting the lamp socket and by adjusting the reflector, the forwardly projected rays of the lamp may be combined and directed as desired.

Other objects and advantages will appear from the drawings and specification.

The drawings illustrate the headlight.

Figure 1 is a front elevation upon a reduced scale of a headlight embodying the principles of our invention, and as seen looking in the direction indicated by the arrow 1 in Fig. 2.

Fig. 2 is a vertical diametrical sectional detail upon an enlarged scale and taken upon the line 2—2 of Fig. 1.

Fig. 3 is a fragmentary sectional detail on the line 3—3 of Fig. 2.

The details of the headlight shown in the drawings are as follows:

The lower half 1 of the reflector is rigidly mounted in the lamp structure in the usual way, the upper edge 2 of the lower half 1 being in a horizontal plane and there being a flange 3 extending outwardly from this upper edge 2. A guide wall 4 extends from the flange 3 on one side upwardly around to the flange 3 on the other side, said wall being concentric to the axis of the lamp and straight on planes parallel with the axis. A stop flange 5 extends inwardly from the inner or rear edge of the wall 4. The upper half 6 of the reflector has a lower edge resting upon the flange 3 and the outer circular edge of the half reflector 6 fits the inner face of the wall 4 all the way around from

one flange 3 to the other flange 3 and the stop 5 limits the inward movement of the half reflector 6.

A connector sleeve 7 has a lamp socket 8 fitting therein, an arm 9 attached to the connector sleeve slides in the slot 10 of the tube 16, which latter is rigidly secured to the outer casing 12. A screw 11 passes through the casing 12 and has a threaded engagement with the arm 9. A compression spring 13 surrounds the screw and is positioned between the arm 9 and the inner side of the casing 12. This takes up any looseness. A cotter pin 14 through the screw 11 prevents complete withdrawal of the screw out of the arm 9. An electric lamp 15 is inserted in the connector sleeve 7 and forms contact with the socket 8 in the usual manner. A headed screw 17 is inserted loosely through the outer casing 12 and through an expansion spring 18 and tapped into a nipple 19 extending from the back side of the half reflector 6 near the half sleeve 16, so that by manipulating the screw 17 the half reflector 6 may be moved forwardly or backwardly to the limits of the annular wall 4.

By adjusting the lamp socket 8 forwardly or backwardly, the projected rays of light 20 may be regulated to any desired angle within reason and are preferably directed forwardly and downwardly. Then by manipulating the screw 17 and adjusting the half reflector 6 forwardly or backwardly the angles of the projected rays of light 21 may be varied and preferably are directed forwardly and downwardly at a greater angle than the rays 20 so as to mix with the rays 20 at a distance in front of the headlight.

Thus, we have produced a headlight having a stationary lower half reflector, an adjustable lamp, and an adjustable upper half reflector.

It is obvious that the glare of the headlight is under control, that the projected rays may be concentrated or spread as desired, and that the direction of the projected rays relative to the level of the roadway may be accurately adjusted so as to make a satisfactory glareless headlight.

Various changes may be made without departing from the spirit of our invention as set up in the claims.

We claim:

1. A headlight construction comprising a casing adapted to support a lens and reflector, a tube mounted through the center of the casing, a connector sleeve slidably mounted in the tube, a lamp socket in the connector sleeve, an arm extending from the connector sleeve through a slot in the tube, a screw inserted through the casing, through an expansive spring and screw seated through the arm so that by manipulating the screw the connector sleeve may be moved forwardly or backwardly, a lower half reflector rigidly mounted in the casing and extending from the forward end of the connector sleeve, an upper half reflector slidably mounted upon the tube, a screw inserted through the casing and connected to the upper half reflector and an expansion spring upon the screw so that by manipulating the screw the upper half reflector may be moved forwardly or backwardly.

2. A headlight construction comprising a casing adapted to support a lens and reflector, a tube mounted through the center of the casing, a connector sleeve slidably mounted in the tube, a lamp socket in the connector sleeve, an arm extending from the connector sleeve through a slot in the tube, a screw inserted through the casing, through an expansive spring and screw seated through the

arm so that by manipulating the screw the connector sleeve may be moved forwardly or backwardly, a lower half reflector rigidly mounted in the casing and extending from the forward end of the connector sleeve, the upper edge of the lower half reflector being on a horizontal plane, a flange extending outwardly from this upper edge, a guide-wall extending from the flange on one side upwardly around to the flange on the other side, said wall being concentric to the lamp and straight on planes parallel with the axis, a stop flange extending inwardly from the inner or rear edge of the guide-wall, an upper half reflector having its lower edge resting upon the flange and the outer circular edge fitting the inner face of the guide-wall and the inward movement of the half reflector being limited by the stop flange, and slidably mounted upon the tube, a screw inserted through the casing and connected to the upper half reflector and an expansion spring upon the screw so that by manipulating the screw the upper half reflector may be moved forwardly or backwardly.

In testimony whereof we have signed our names to this specification.

GEORGE MATTHYSSEN.
CHARLES OHLSON.
